UNITED STATES PATENT OFFICE.

CHARLES A. WARD, OF SILVER CREEK, NEW YORK.

DESIGN FOR A DINING-CAR BODY.

Application filed January 17, 1927. Serial No. 20,415. Term of patent 3½ years.

To all whom it may concern:

Be it known that I, CHARLES A. WARD, a citizen of the United States, residing at Silver Creek, in the county of Chautauqua and State of New York, have invented a new, original, and ornamental Design for a Dining-Car Body, of which the following is a specification, reference being had to the accompanying drawings, forming part thereof:

In the accompanying drawings:

Figure 1 is a perspective view of a dining car body embodying my new design, viewed from one side. Figure 2 is a similar view from the opposite side of the same.

I claim:

The ornamental design for a dining car body as shown.

CHARLES A. WARD.
